ABSORBENT PAD DIAPER

Kenneth Hurst, Altamont, Tenn.

Application February 21, 1947, Serial No. 729,933

5 Claims. (Cl. 128—284)

1.

This invention relates to diapers of the pinless preformed type, and in particular, a diaper having a pouch with a perforated wall positioned on the inner surface in which an absorbent pad may be held.

The purpose of this invention is to provide absorbing means in a diaper wherein all fluids will be contained in the absorbing means, thereby eliminating the possibility of damp or wet clothing and also eliminating the possibility of chafing and the like.

In the usual form of diaper, particularly of the absorbent type, the wet material is in direct contact with the surface of the skin of the wearer, and after saturation the excess moisture is absorbed by the clothing. With this thought in mind, the diaper of this invention includes an enclosed absorbent element wherein fluids will pass through the perforations in the wall of a pocket in which the absorbent element is positioned and will remain in the absorbent material so that they will not spread over the skin of the infant or contact the clothing.

The object of this invention is, therefore, to provide means for incorporating an absorbent pad in a pouch in a diaper wherein the absorbent pad is positioned to receive substantially all fluids discharged in the diaper.

Another object of this invention is to provide a diaper having an absorbent pad-holding pouch in which the end of the pouch is flared to facilitate inserting and removing the pad.

Another object of the invention is to provide an improved diaper having an absorbent pad-holding perforated pouch incorporated therein which is of the pinless type.

A further object of the invention is to provide a diaper having an absorbent pad incorporated in a perforated pouch therein which is of a simple and economical construction.

With these and other objects in view, the invention embodies a diaper of substantially rectangular shape with leg openings in the sides and beveled ends, a pouch, the edges of which are secured to the material of the diaper wherein one end of the pouch is extended and flared to facilitate inserting and removing a pad, and an absorbent pad adapted to be inserted in the pouch. The material of the diaper and pouch is preferably a thin plastic or non-absorbent material, and the inner surface of the pouch is perforated to facilitate passage of moisture therein.

Other features and advantages of the invention will appear from the following description taken in connection with the drawings, wherein:

2.

Figure 1 is a view looking toward the inner surface of the diaper with the pouch indicated in dotted lines and with perforations extending through the material of the diaper.

Figure 2 is a similar view showing the outer surface of the diaper with the pouch and outwardly flared opening thereof illustrated thereon.

Figure 3 is a cross-section through the diaper on line 3—3 of Figure 1, showing the pouch with an absorbent pad therein.

Figure 4 is a detail showing a section through an edge of the diaper illustrating a reinforcing hem around the edges thereof.

Figure 5 is a detail showing a section through an edge of one of the leg openings in the sides of the diaper illustrating a cord incorporated in a hem thereof.

Figure 6 is a view illustrating a method of forming the pouch on the surface of the diaper with parts of the diaper broken away.

Referring now to the drawings, wherein like reference characters indicate corresponding parts, the diaper of this invention includes a sheet of thin waterproof plastic or other non-absorbent material 10, a pouch 11 and an absorbent pad 12.

In the design shown, the diaper is provided with leg openings 13 and 14, ends 15 and 16 and sloping surfaces 17 and 18 adjacent the end 15 and 19 and 20 adjacent the end 16. The edges of the diaper are provided with a continuous hem 21 that may be provided with a reinforcing strip of fabric 22 and the inner edge may be secured to the sheet by an adhesive or stitches as may be desired, as indicated at the point 23. The edges of the material around the leg openings may be reinforced by an elastic cord 24 in a bead 25 and the folded-over edge 26 of the bead may be secured to the material of the diaper by stitching or a suitable adhesive.

The pouch 11 is preferably formed as shown in Figure 6 with the edges thereof provided with flanges 27 and 28 that may be secured to the material of the diaper by an adhesive or by stitching, and one end 29 is closed, while the opposite end is provided with an outwardly flared or funnel-shaped neck 30 which facilitates inserting an absorbent pad 12 or the removal of the pad therefrom.

Buttons 31 may be provided on the corners of the outer part of the diaper and buttonholes 32 may be provided in the hem of the opposite section, and although buttons and buttonholes are disclosed, it will be understood that fasteners of any type may be used.

The pad 12 may be formed of any suitable absorbent material, and the surface of the diaper registering with the pouch is provided with perforations 33. The perforations and pouch are positioned wherein substantially all fluids discharged into the diaper will pass through the perforations so that they may be absorbed by the absorbent pad.

All fluids discharged into the diaper pass through the perforations to the absorbent pad in 10 the pouch, thereby eliminating wetness from the skin of the infant, wherein the diaper will have the feel of a dry diaper, providing greater comfort to the wearer.

In order to provide a snug fit around the waist 15 of the wearer, elastic strips 34, as indicated by the dotted lines in Figures 1 and 2, are provided in the hems or waistbands 15 and 16 at the ends of the diaper. This will provide a slight tension around the waist, preventing the diaper from 20 slipping downward.

The improved diaper of this invention, therefore, includes a diaper of usual configuration with leg openings and front and back bands, and in addition, a pouch formed in the intermediate part of the diaper with an absorbent pad in the pouch and with perforations in the diaper or wall of the pouch, wherein fluids discharged in the diaper will be absorbed by the pad and thereby removed from contact with the skin of the wearer 30 of the diaper.

The diaper of this invention is illustrated in the preferred form, although it will be understood that modifications may be made in the design and arrangement of the parts without departing 35 from the spirit of the invention.

What is claimed is:

1. In a diaper of the preformed pinless type, the combination, which comprises a sheet of non-absorbent material having an inner and outer surface and having leg openings in the sides with front and rear waist bands at the ends, a pouch positioned on an intermediate part of the outer surface of said diaper, and an absorbent pad positioned in said pouch, said diaper having perforations formed through said sheet and opening into said pouch from said inner surface, and an access opening in said pouch outwardly of said outer surface.

2. In a diaper of the preformed pinless type, 50 the combination, which comprises a sheet of non-absorbent material having an inner and outer surface and having leg openings in the sides with

5 front and rear waist bands at the ends, a pouch positioned on an intermediate part of the outer surface of said diaper, said diaper having perforations formed through said sheet and opening into said pouch from said inner surface, and an adsorbent pad positioned in said pouch, said pouch having an outwardly flared funnel-shaped end outwardly of said outer surface to facilitate inserting the absorbent pad.

3. In a diaper of the preformed pinless type, the combination, which comprises a sheet of non-absorbent material having leg openings in the sides with front and rear waist bands at the ends, a pouch with a perforated surface positioned in an intermediate part of the diaper, and an absorbent pad positioned in said pouch, said pouch having an outwardly flared funnel-shaped end to facilitate inserting the absorbent pad, and said diaper having hems with reinforcing strips therein at the edges and beads with elastic elements therein in the leg openings.

4. In a diaper of the preformed pinless type, the combination, which comprises a sheet of non-absorbent material having leg openings in the sides with front and rear waist bands at the ends, a pouch with a perforated surface positioned in an intermediate part of the diaper, an absorbent pad positioned in said pouch, said pouch having an outwardly flared funnel-shaped end to facilitate inserting the absorbent pad, and said diaper having hems with reinforcing strips therein at the edges and circular elastic beads in rolls extending around the leg openings, and fastening devices on the hems of the diaper.

5. A diaper, comprising a sheet of non-absorbent material, said sheet having inner and outer surfaces, said sheet being formed to provide a plurality of perforations therethrough centrally thereof, a pouch for absorbent material on said outer surface of said sheet and overlying all of said perforations, and an access opening in said pouch outwardly of said outer surface.
